PISTON CYLINDER RIDGE REAMER DRIVE
CASING

Orrin E. Lewis, Belleville, Kans.

Application December 12, 1955, Serial No. 39,276

Term of patent 14 years

(Cl. D54—14)

Fig. 1 is a side elevation of a piston cylinder ridge reamer drive casing, showing my new design;

Fig. 2 is a side elevation of same as viewed from the left-hand side of Fig. 1; and

Fig. 3 is plan view of the casing as shown in Fig. 2.

The dominant features of my new design are shown in solid lines in the drawing.

I claim:

The ornamental design for a piston cylinder ridge reamer drive casing, substantially as shown and described.
